(57) **CLAIM**

The ornamental design for a compact juicer, as shown and described.

DESCRIPTION

FIG. 1 is a front elevation view of a compact juicer showing my new design;

FIG. 2 is a right elevation view thereof;

FIG. 3 is a rear elevation view thereof;

FIG. 4 is a left elevation view thereof;

FIG. 5 is a top view thereof;

FIG. 6 is a bottom view thereof;

FIG. 7 is a front perspective view thereof; and,

FIG. 8 is a rear underside perspective view thereof.

The broken lines are for illustrative purposes only and form no part of the claimed design.
